United States Patent Office.

JAMES M. CROCKETT, OF NEWBERN, VIRGINIA.

Letters Patent No. 71,711, dated December 3, 1867.

DRAUGHT AND VENTILATING-DEVICE FOR OPEN GRATES, &c.

The Schedule referred to in these Letters Patent and making part of the same.

TO ALL WHOM IT MAY CONCERN:

Be it known that I, JAMES M. CROCKETT, of Newbern, of the county of Pulaski, and State of Virginia, have invented a new and useful "Mode of Ventilating Chimneys" to dwelling and other houses called the "Chimney-Ventilator;" and I do hereby declare the following to be a full and exact description thereof, reference being had to the accompanying drawings, and to the letters of reference marked thereon, making a part of this specification.

The nature of my invention consists in the arrangement and construction of the box, damper, lid, and pipe, for the purpose of furnishing an air-passage from the nearest point outside of the house, to a point immediately in front of the fire, by means of the pipe passing from said point outside of the house, and under the hearth, and then connecting with a receiving and distributing-box, that passes upward through the hearth at the point in front of the fire.

This invention prevents all chimneys from smoking, that would otherwise do so from want of sufficient ventilation, and also relieves the room from all unpleasant draughts of cold air, and unpleasant sounds produced by the air passing through the doors and windows, and also greatly facilitates the kindling of the fire, as well as the warming of the room.

Figure 1 represents a front view of the ventilator.

Figure 2 a side elevation.

The receiving and distributing-box A, as shown on the drawing, projects an inch above the hearth, and on the front towards the fire-place contains a number of apertures, B B, proportionate to its length, and is supplied with a damper, C, regulating the supply of air that may be found necessary. The said box A should be about four inches wide by twelve inches long, and should pass three inches or more below the top of the hearth, so as to receive the pipe D, which is about two and a half inches in diameter, and located one inch above the bottom of the box. The box A is covered with a suitable lid, E, which may be removed at pleasure for cleansing. The pipe D is made in sections, so that its length may be readily adapted to the required distance, and the end on the outside of the house is provided with a wire-screen cap, G, to prevent it from being choked. The box A and pipe D should be made of cast iron. The lid E of the box A may be made level with the hearth, instead of being elevated, and in that case the vents and damper may be placed in the lid. H is a line to represent the top of the hearth. J is a line representing the bottom of the hearth. The hearth is supposed to be made of brick three inches thick. K represents the grate of the fireplace.

What I claim as my invention, and desire to secure by Letters Patent, is—

The arrangement and construction of the box A, damper C, lid E, and pipe D, when combined as herein described and for the purposes set forth.

JAMES M. CROCKETT.
